BOTTLE CLOSURE

Allan I. Roskkind, Chicago, Ill., assignor to A. B. Dick Company, Chicago, Ill., a corporation of Illinois

Application April 26, 1949, Serial No. 89,639

5 Claims. (Cl. 215—43)

1

This invention relates to closures, and more particularly to a screw threaded closure having particular merit when used with containers for packaging content material having volatile constituents in order to minimize the loss of such volatiles by evaporation.

Very often, substances, either consisting of or diluted with volatile materials and solvents are packaged in containers adapted to make the content material conveniently available for intermittent use as the occasion demands. The user may have several calls for the material within a short space of time, such as in the use of eradicating fluid in stencil duplication, and on such occasions, it has been found by practical experience, that the user invariably makes only a slight pretense at properly positioning the closure on the container permitting possible loss of content material by evaporation. Yet, gradual loss of the volatile constituents soon renders the remaining substance unfit for the purpose for which it was intended.

Various means have been devised by suppliers of such materials to prevent such careless and haphazard use but such practices have suffered from increased costs or from the resistance of the purchaser to the more regimented technique.

Loss by evaporation not only occurs from improper placement of the closure, but it has been found that a large number of packages are improperly sealed with conventional caps even when tightly screwed upon the bottle or container with the result that losses occur during shipment and storage, especially when the volatile constituents comprise low boiling solvents of the type ether and alcohol. Evaporation under such conditions may be aggravated upon exposure to relatively high temperatures which increase internal pressure within the container.

It is an object of this invention to provide a closure which is adapted to establish a proper sealing relation with the container even when positioned in a careless and haphazard manner.

Another object is to produce a closure capable of establishing an improved sealing relation more efficiently to resist evaporation of content material when the closure is properly positioned.

A further object is to provide a closure which is not unlike conventional closures in application but which is capable of establishing a sealing relation on the slightest pretense of replacement to compensate for careless operation.

More particularly, it is an object of this invention to provide a screw threaded closure which will establish an improved sealing relation when

2

properly screwed into place and which will still provide a sealing relation in the event that the operator fails properly to screw the closure into place or in the event that the operator merely positions the closure over the opening of the container.

The objects of this invention are achieved with a threaded closure having an integral part which establishes a sealing relation with the neck of the bottle or container merely upon placement of the closure in proper relation on the container. The sealing relation is further improved if the closure is screwed onto the container, and when properly screwed down, a new sealing relation is established which is far more efficient than that heretofore secured by conventional caps.

Fig. 1 shows separate perspective views of the container and the cap assembly.

Fig. 2 is an elevated cross-sectional view of the cap immediately on engagement of the inner tubular element with the container and before threaded engagement between container and cap skirt.

Fig. 3 is an elevated cross-sectional view of parts in final sealing disposition.

Description of my new and improved closure will be made in connection with a bottle having a screw neck and an annular portion bulging inwardly from a spaced apart portion of the rim of the neck. Although the bulging portion imparts some advantages as will hereinafter be pointed out, its presence is not necessary for the successful operation of the closure.

The closure has a top wall 10 with a threaded skirt 11 depending integrally from the outer rim of the top wall and dimensioned threadably to engage the threaded end 12 of the neck 13 of the bottle 14. Depending integrally from an intermediate portion of the top wall 10 is a substantially concentric resilient tubular member 15 dimensioned to enter the opening 16 in the neck and to engage the internal wall of the neck all around in sealing relation immediately upon entrance.

The tubular member 15 is formed with a gradual taper having its greatest thickness at the base where it joins the top wall while the outer end portion 16 is tapered inwardly at a sharper angle to facilitate entrance of the tubular member 15 into the neck and to operate as a self centering element for the closure. The tubular member is made to extend beyond the threaded portion of the skirt 11 for the purposes of establishing a sealing relation all around in the prevention of

loss of the content material from the bottle even though the closure may be carelessly pushed into place but not properly secured in place by screwing.

For uses wherein the content material is to be made with an applicator, the closure may be provided with a central hub section 17 tapered inwardly at a slight angle to provide a resilient gripping cavity 18 for properly receiving the end of a shaft 19 which may constitute part of an applicator, such as the brush 20 shown in the illustrated drawing. To facilitate turning movement of the closure into and out of threaded engagement with the container, the outer wall of the closure may be formed with a plurality of ribs 21 or it may be otherwise provided with gripping surfaces.

In order to establish a sealing relation which increases as the tubular member sets farther and farther into the neck, the tubular member should be formed of a resilient substance, and it is expedient if the entire closure be formed of such substances which of necessity should be impervious to the content material. Suitable materials, with and without softeners and plasticizers, may be selected of the harder rubbers and vulcanized rubbers, neoprene, polyethylene, vinyl polymers and copolymers such as polyvinyl chloride, vinyl chloride-vinyl acetate copolymer, polyvinylidene chloride and copolymers thereof with vinyl chloride and vinyl acetate.

As shown in Figure 2 a sealing relation is established between the lower end portion of the tubular member 15 and the neck 13 as soon as the member enters the neck portion. As the tubular member is actuated farther into the neck portion, it is further deformed by the bulging portion 22 to establish a more effective seal. When, finally, the closure is tightly screwed upon the neck, it will be apparent that a sealing relation exists throughout the length of the tubular member which augments the sealing relation which is firmly established between the rim of the neck and the underside of the top wall of the closure. The tubular member not only provides for a considerably greater amount of sealing surface but it reduces access of the content material and its vapors to the area between the rim and the closure, which might otherwise permit loss by evaporation because of an improper fit not infrequently encountered in commercial units.

By the arrangement described, it will be further apparent that any internal pressure which might be built up by the content material will operate to press the tubular member against the neck of the container thereby further to improve, as the occasion demands, the sealing relation.

It will be understood that numerous changes may be made in the details of construction, arrangement and operation without departing from the spirit of the invention, especially as defined in the following claims.

What is claimed is:

1. A closure comprising a top wall, a screw threaded skirt depending from the top wall for threaded engagement with the outer wall of the neck of the container, a tubular sleeve substantially concentric with the skirt depending from an inner portion of the top wall and dimensioned to be of slightly greater outside diameter than the inner diameter of the neck and of greater length than the threaded portion of the skirt whereby the side wall of the tubular sleeve is deflected inwardly and a sealing relation is estab-

lished even before the threaded engagement is effected, and a cylindrical section depending from the central portion of the top wall in concentric spaced relation with the sleeve, a dispenser having a supporting shaft, and means forming a part of the cylindrical section for securing the end of the shaft thereto in the assembled relation.

2. A closure for use on a container having a threaded neck comprising a top wall, a screw threaded skirt depending from the top wall for threaded engagement with the outer wall of the neck of the container, a tubular sleeve substantially concentric with the skirt and spaced inwardly therefrom and dimensioned to be of greater length than the skirt and to establish a sealing relation with the inner wall of the neck thereof before threaded engagement is effected, a dispenser, and means depending from a central portion of the wall in inwardly spaced relation with the sleeve for supporting the dispenser in position of use.

3. A closure as claimed in claim 2 in which the outer end portion of the tubular sleeve is tapered inwardly to facilitate entrance thereof into the neck of the container in advance of threaded engagement.

4. A closure as claimed in claim 2 in which the tubular sleeve is dimensioned to be of smaller outside diameter than the opening of the neck of the container in the outer end portion thereof and of greater diameter through the major portion of the remainder thereby to facilitate entrance of the tubular member into the neck of the container and establish a sealing relation therewith upon insertion.

5. A closure for use in establishing a sealing relation with a container having an annular bulge spaced a short distance from the threaded neck of the container, said closure comprising a top wall, a screw threaded skirt depending from the top wall to bring the top wall in sealing relation with the rim upon actuation of the closure into position of use, a tubular section depending from the top wall in concentrically inwardly spaced relation from the skirt and dimensioned resiliently to engage the inner wall of the neck of the closure upon insertion before threaded engagement and to be further engaged all around by said bulge upon tightening the closure onto the container for purposes of increasing the sealing relation, a dispenser, and means depending from a central portion of the wall in spaced relation with the tubular section for supporting the dispenser in position of use.
